UNITED STATES PATENT OFFICE.

CHARLES D. SEEBERGER, OF YONKERS, NEW YORK.

CONVEYER.

No. 900,000.

Specification of Letters Patent.

Patented Sept. 29, 1908.

Application filed November 24, 1902, Serial No. 132,513. Renewed December 7, 1904. Serial No. 235,882.

To all whom it may concern:

Be it known that I, CHARLES D. SEEBERGER, a citizen of the United States, residing at Yonkers, in the county of Westchester and State of New York, have invented certain new and useful Improvements in Conveyers, of which the following is a specification.

My invention relates to conveyers and primarily is concerned with certain new and useful improvements in the driving mechanism of that type or class of conveyers which are in the form of an endless series of steps running on different horizontal planes connected by inclined portions, and my improvements are designed to reduce the strains on the apparatus incident to the changes in the direction of movement which have been inevitable as these devices have been hitherto constructed.

My invention is further concerned with certain improvements in the structure of these devices by which a single carrier running in a single vertical plane and having its descending portion directly beneath its ascending portion, or vice versa, can be used for conveying purposes on both portions. This feature of my invention is especially applicable to traveling stairways, and necessitates a construction in which the tread surfaces of the steps or supports shall remain horizontal and uppermost in both the ascending and descending portions, a requirement that has been impossible with these devices as hitherto constructed.

My invention is further concerned with certain novel combinations of elements and structures employed, as will be fully set out in the description of the apparatus and specifically pointed out in the claims.

To illustrate my invention, I annex hereto four sheets of drawings in which the same reference characters are used to designate identical parts in all the figures, of which—

Figure 1 is a side elevation, diagrammatic in its nature, showing an arrangement of tracks in which my system may be employed, and indicating the arrangement of the driving connections; Fig. 2 is a vertical section of the same on the line A—A of Fig. 1, but on a greatly enlarged scale; Fig. 3 is a side elevation of the tracks at the upper end carriage thereof, showing in full lines a few of the yokes on the adjacent ends of the steps in position, and indicating the position of the remaining yokes and the steps in dotted lines; Fig. 4 is a horizontal section of the same substantially on the line B—B of Fig. 3; Fig. 5 is a view similar to Fig. 3, but showing the lower end carriage of the tracks; and Figs. 6, 7 and 8 are sectional views on the lines C—C, D—D and E—E, respectively, of Fig. 5, the associated parts of the steps being shown in relative positions by dotted lines.

Premising that the tread surfaces of the steps remain uppermost throughout the entire line of transportation, and that the steps are connected throughout by one or more chains which move in the direction of the arrows of Fig. 1, and in the path indicated by the heavy line 11, Fig. 1 represents a side elevation of the tracks, and the gearing connecting the various portions of the chain or line of steps to control the movement of the driving mechanism.

In the design shown, the passenger steps on the traveling stairway at the lowermost ascending landing 12, whence he is carried up the incline 13 to the horizontal landing 14, where he may get off on the second floor, if he desires, or continue up to the third floor, being carried up the incline 15 to the horizontal landing 16 on the third floor, where the traveling stairway terminates in the particular design shown. The steps then descend about the upper end carriage 17 to the second floor, where a horizontal landing 18 is formed for people who desire to get on the traveling stairway to descend to the first floor, those embarking on this landing being carried down the incline 19 to the horizontal landing 20 on the first floor where they can get off. The line of steps then descend at 21, and ascend around the curve 22 constituting the lower end carriage and emerge on the landing 12. It is apparent from Fig. 1 of the drawings that in the present design of the machine, portions of both the ascending and descending runs provide landings which are in the same horizontal plane at each floor or level; for example, the landings 12 and 20 at the first floor are in the same plane, and the landings 14 and 18 at the second floor are also in the same plane. These steps are all connected together by preferably two rack link chains extending the entire course, and, as hereinafter shown, located at the ends of the steps. The power for running the traveling stairway is supplied by the motor 23, which gears with a pinion 24 (see Fig. 2) which is secured on the outer end of a transverse shaft 25 journaled in

suitable bearings formed in supports 26 projecting downward from the under side of the channel bars 27 which form the supports for the tracks on the inclined and horizontal portions. In the particular construction shown in Fig. 2, the shaft 25 is shown as provided with the gear wheels 28 secured thereto near the ends and projecting upward through the apertures 29 formed in the under webs of the channel bars 27 and meshing with the rack links of the chains 30. Secured on the shaft 25 between the pinion 24 and the adjacent channel bar 27 is the bevel gear pinion 32, which meshes with the bevel gear pinion 33 secured upon the vertical shaft 34 journaled in suitable bearings (not shown), and having the bevel gear pinion 35 on its lower end meshing with the bevel gear pinion 36 secured on a transverse shaft 37 which is similar to the shaft 25 and is provided with the same gear wheels for engaging the rack links 30 of the chains 11 at the point where it is located at the upper end of the incline 19. The gear connections between the shafts 25 and 37 are such that their rotation drives the chains in the proper direction. At the upper end of the incline 13, I locate another transverse shaft 38, which like the shafts 25 and 37 is provided with gear pinions and mechanism for engaging the chains 11. A short distance above the beginning of the incline 15 I locate another transverse shaft 39 which is also provided with the gear pinions and mechanism for engaging the chains 11, and I connect these two shafts 38 and 39 by means of bevel gear pinions and an inclined shaft 40 so that the two shafts 38 and 39 are compelled to move in unison with each other, and as they are driven by the chains 11, they move in unison with the shaft 25. Just above the beginning of the incline 19, I locate another transverse shaft 41, which, like the shafts 25 and 37 is provided with gear pinions and mechanism for engaging the chains to be rotated therewith. In the horizontal landing 20 just in advance of the beginning of the incline 19, I locate another transverse shaft 42 similarly provided with gear pinions for engaging the chains, and I connect these two transverse shafts 41 and 42 by means of suitable bevel gear pinions and an inclined shaft 43, so that the shafts 41 and 42 are compelled to rotate in unison. I may also connect the shafts 38 and 41 by means of bevel gears and a vertical shaft 44, so that the four transverse shafts 38, 39, 41 and 42 are compelled to rotate in unison as they are driven by the chains. At a point just above the beginning of the incline 13, I locate another transverse shaft 45, and just previous to the beginning of the incline 13 I locate another transverse shaft 46, and connect the two by means of the customary bevel gear pinions and the inclined shaft 47, the shafts 45 and 46 being

provided with the customary gear pinions for engaging with the chains. Near the top of the incline 21 I locate another transverse shaft 48, which is provided with the customary spur gear pinions for engaging the chains, and is connected by the customary bevel gears and shaft 49 with the shaft 46. The purpose of these various transverse shafts is as follows: The power for driving the entire system is shown as applied to the shaft 25, and if no transverse shafts were employed, it will be apparent that the pull on the chains would tend to raise them at the angles between the landing 14 and the incline 15, and between the landing 12 and the incline 13. The tension on the chains would also cause them to bear down very hard and bind on the angle between the incline 13 and the landing 14, and the weight of the lower half of the chain or line of steps would cause it to pull very heavily on the end carriage 17, the landing 18, and especially on the angle between the incline 19 and the landing 18. Likewise the pull caused by the weight of the lower half of the chain of steps would tend to raise it as it passed the angle between the horizontal surface 20 and the incline 19.

As the steps are assembled, the distance between the shafts 38 and 39 is so calculated that the chains connecting the steps between these two points will be comparatively loose. The same adjustment is employed between the shafts 45 and 46, and between the shafts 41 and 42, between the shafts 25 and 37 around the end carriage 17, and between the shafts 46 and 48 around the end carriage 22. With this arrangement of parts, when the mechanism is run, the chains on the incline 15 down to the shaft 39 will be under tension, but from the shaft 39 to the shaft 38, the driving power is transmitted through the shaft 40, and the chains in running over the two angles will be comparatively loose and free from any tension. From the shaft 38 down to the shaft 45 the chains will again be under tension as is necessary on the lift of the incline. From the shaft 45 to the shaft 46 the chains are loose, and the driving power is transmitted from the shaft 45 to the shaft 46 through the shaft 47, leaving the chains loose. Similarly, the shafts 25 and 37 being geared together and connected to the chain of steps, the chains run comparatively loosely on the landings 16 and 18 and around the end carriage 17, while they are under tension due to the weight of the steps and the load that may be on the incline from the shaft 37 to the shaft 41. From the shaft 41 to the shaft 42, the pull of the steps is taken by the gear mechanism through the shaft 43 and the chain of steps is loose between the shafts 41 and 42. The shaft 48 connected to the shaft 46 by the shaft 49 insures paying out the chains and steps to the carriage on the end 22 in unison with the

general movement, and is a means of taking the strain off of the junction of the incline 21 with the landing 20. With this arrangement of parts, which may be varied as much as 5 may be necessary for different designs, it will be apparent that I can keep the chains taut and under tension on the inclines, while they are kept loose in passing the angles so as to do away with unnecessary friction, and thus 10 enable me to more perfectly control the operation of the apparatus, dispensing with friction, grinding and noise. The employment of these transverse shafts connected as shown also serves to cut the system up into sections 15 which are in equilibrium through the balancing of the ascending and descending portions. It will be apparent that instead of employing the transverse shafts geared together by the inclined shafts, I might run these various 20 transverse shafts by motors suitably synchronized, as indicated in dotted lines at 50 and 51, and obtain the same results in that manner. This feature of my invention is of far reaching importance, and I do not desire 25 to be limited to the employment of any specific mechanism for obtaining the results herein set forth.

Referring now to Figs. 3 to 8, the second feature of my invention consists in the novel 30 form of step employed and tracks with which they coöperate by which I am enabled to use both the ascending and descending inclined portions in the same plane and one above the other for the purpose of carrying 35 passengers both up and down. The steps 52 are of the same general construction which I have hitherto employed, as shown in my application No. 79,520, filed October 22, 1901, except that the arms 53 and 54 constituting the yoke which carries the rear and 40 front wheels 55 and 56, respectively, are not in the same horizontal plane, but are separated by an angle so that on the inclined portions of the tracks, as shown in section 45 in Fig. 2, the two tracks for the front and rear wheels are in substantially the same horizontal plane, instead of being arranged as upper and lower tracks as in the form shown in my prior application. On the horizontal 50 landing portions, however, the tracks 57 for the rear wheels 55 are below the tracks 58 for the front wheels 56, and the angles between the arms 53 and 54 are such with relation to the angle of the inclined end that 55 the tread surface of the step, which is rigidly secured relative to the arms 53 and 54, will always be horizontal on all the inclines and landings, and, in the design shown, also as the steps are passing around the curves at 60 the ends.

The angular formation of the yokes is important because in going off an incline to a horizontal run, or vice-versa, it allows for clearance to avoid striking the tracks; otherwise 65 it would be necessary in the form shown

to provide gaps in the track at such points to be controlled by a switch which would of course be a complicated structure and liable to easy derangement. The yokes of each step are connected by a step-bar or rod 59; 70 these parts may be rigidly connected or the yokes may be loose upon these rods. Instead of having the steps connected by a single central chain, I preferably employ the two chains made up of the rack links 30, 75 which are of the same general construction as those shown in my aforesaid application, but which are pivoted on the outer ends of the step-bars or rods 59, and run next to the sides of the channel beams 27, as clearly 80 shown in Fig. 2. I preferably secure on the step-bars 59, between the chains and the yokes, the collars 60, which coöperate with the channel guides and tracks hereinafter described. 85

Referring now to Fig. 3, which shows the tracks around the upper end carriage connecting the upper ends of the way formed by the tracks 57 and 58, the horizontal landing portion of the track 57 for the rear wheels 55 runs into the channel track 61, which, as clearly shown in said figure, extends around the end in a substantial U-shape, and is arranged to coöperate with the wheels 55 on two sides to prevent any movement thereof 90 except in the line of the track. This channel track is continuous around the end, except where it is interrupted, as seen at 62 and 63, for the passage of the step-bars 59 in one place. While the channel track 61 is continuous except for the interruption noted, it is made up of the upper main part which I have lettered 61, and of the lower part, which I have lettered 61^a, each part being supported by suitable brackets connected to the 100 built-up channel bars 64 forming the outer structure at the ends of the track. The upper portion of the track 58 for the upper wheels 56 terminates in the channel track 65, which is also of a substantially U-shape, and 110 the outer flange thereof is continuous, but the inner flange is interrupted at two points, 66 and 67, to permit the passage of the outer extremities of the axle bars 59. The movement of the steps about this upper end carriage will now be apparent, by reference to Fig. 3, and to the yokes and wheels, most of which are shown in dotted lines to avoid covering up the tracks. The steps maintain 115 their horizontal position throughout, and as the upper wheels 56 cross the gap 66 in the channel tracks 65, the step is held up and in proper position by reason of the collars 60 resting on the step bar guide or track 68, which is suitably supported by a bracket 120 from the structure 64. The steps now follow around the tracks without interruption until the wheels 55 cross the gaps 62 and 63 and the wheels 56 cross the gap 67, the steps being held in proper position as above de- 125 130

scribed. These gaps are passed by reason of the collars 60 coöperating with the channel-guide formed by the two axle bar tracks 69 and 70 suitably supported by brackets from the structure 64 at the upper and lower sides thereof. The steps are thus guided upon the horizontal returning portions of the tracks 57 and 58, but it will be observed that the direction of movement of the steps has been 10 changed without inverting the steps or changing the position of the riser sides, so that the single fixed risers can be employed both on the ascending and descending portions of the tracks, a possibility that, so far 15 as I am aware, is entirely novel.

Referring now to Fig. 5, which illustrates the lower carriage connecting the lower ends of the way formed by the tracks 57 and 58, as the steps reach the limit of their down- 20 ward movement, the upper wheels 56 pass from the horizontal portion of the tracks 58 into the channel track 71, which serves to guide the steps about the lower end in the same manner as did the channel track 65 25 about the upper end. There is a gap formed at 72 between the outer flange of the channel track 71 and the track 58 to permit the passage of the axle bars 59, and the step is held in its vertical position as it passes this gap 30 by the collars 60 coöperating with the guide track 73, which is supported by a suitable bracket extending from the built-up channel structure 74 forming the supports for the tracks around the lower end. The lower 35 wheels 55 pass from the horizontal portion of the track 57 into the substantially U-shaped channel track 75, which is continuous except for the interruptions at 76 and 76^a necessitated by the passage of the axle-bars 55 at 40 this point. These interruptions at 76 and 76^a necessitate the channel track 75 being made in two parts, the lower main portion of which I have lettered 75, and the upper shorter portion of which I have lettered 75^a, 45 each portion being supported by suitable brackets from the structure 74. To carry the steps over the gaps 76 and 76^a and keep them in proper position, I provide the upper and lower channel-guides formed by the 50 tracks 77 and 78 suitably supported by the brackets from the structure 74, and coöperating with the collars 60 on the axle-bars 59. By means of the end-carriages or reversers at 55 both ends of the machine, as herein described, I am enabled to carry the steps with their tread surfaces horizontal about the upper and lower ends, and reverse the direction of movement thereof so that they are ready 60 to carry the passengers up the inclines 13 and 15 and down the incline 19.

The purpose of the carriages at the ends of the machine is to present or deliver the steps in horizontal position at the carrying or transporting portions of the runs. In passing 65 through the carriages the steps may or

may not be retained with their treads horizontal, although in the present embodiment I do so retain them, the essential feature in this respect being that they shall be presented or delivered with their treads in horizontal position at the places where they receive their load.

While I have herein shown my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States is—

1. In conveying apparatus, a series of supports, guiding and driving means for said supports forming a plurality of transporting runs having inclined portions, said guiding means maintaining one face of each of said supports in substantially parallel position throughout said inclined portions, and reversers to transfer said supports between said runs.

2. In conveying apparatus, a series of supports, guiding and driving means for said supports forming a plurality of transporting runs having horizontal and connecting inclined portions, said guiding means maintaining corresponding faces of said supports in substantially parallel position throughout said inclined and horizontal portions, and reversers to transfer said supports between said runs.

3. In a conveying apparatus, the combination with the ways extending to different levels and having portions thereof extending in different angular directions, of an endless conveyer coöperating with said ways, mechanism for driving said conveyer, and means connecting portions of said conveyer adjacent the angles so as to transmit the driving strain past said angles removing the tension from the conveyer as it passes said angles.

4. In a device of the class described, the combination with the ways extending in different angular directions, of an endless conveyer coöperating with said ways and composed of a series of steps connected by a chain, means for driving the conveyer, spur gears meshing with said chain adjacent the angles, and connections between the spur gears on the two sides of the angles so as to transmit the driving strain past said angles removing the tension from the chain as it passes them.

5. In a conveying apparatus, the combination with the ways extending to different levels and portions thereof extending in different angular directions, of an endless conveyer coöperating with said ways and composed of a series of steps connected by

- a chain, means for driving the conveyer, spur gears meshing with said chain on both sides of an angle therein, and a countershaft extending past the angle having bevel gear connections with said spur gears on each side of the angle so as to transmit the driving strain past the angle thereby removing the tension from the chain between the gears.
6. In a conveying apparatus, the combination with the ways extending to different levels and having portions thereof extending in different angular directions, of an endless conveyer coöperating with said ways and composed of a series of steps connected by a pair of driving chains located at the ends of the steps, a pair of spur gears meshing with said chains to drive the conveyer, a pair of shafts on opposite sides of an angle each having a pair of spur gears meshing with the chains, and connections between said shafts compelling their movement in synchronism and operating to transmit the driving strain past the angle removing the tension from the chains as they pass it.
7. In a device of the class described, the combination with a series of steps connected by a pair of driving chains, of ways in which said steps travel, said ways including landing portions at different levels and an inclined portion connecting the same, driving mechanism for said chains located in the inclined portion adjacent to the upper landing, and means to reduce the tension of the chains at the angles.
8. A moving stairway consisting of upper and lower transporting portions, means for driving the stairway, gears independent of the driving means and engaging the said portions respectively, and a connection between the gears.
9. A moving stairway consisting of upper and lower carrying portions, a motor having driving connection with the stairway, transverse shafts connecting respectively with the upper and lower portions, and connections between the shafts.
10. A moving stairway comprising parallel endless chains having steps and providing upper and lower carrying portions, means for driving the stairway, a transverse shaft associated with each portion and having spur gears engaging the chains, and a shaft connecting the transverse shafts.
11. In a device of the class described, a step provided with an axle bar having angular wheel-carrying yokes at its ends to bring the wheel on one arm of each yoke above the wheel of the other arm.
12. In a device of the class described, a step consisting of the axle bar having the step proper secured thereto and having the yoke arms extending therefrom at different angles from the perpendicular to bring the wheel on one yoke arm above the wheel on the other arm.
13. A moving stairway comprising a series of steps, each step having an angular yoke at each end, wheels in the yokes, and tracks adapted to present the treads uppermost on the runs with the leading wheels on one run following on the other run.
14. In a device of the class described, the combination with the tracks forming a continuous way in a single vertical plane and with the ascending and descending portions covering the same surface, of a set of steps coöperating with said tracks, and driving connections for said steps, the tracks and steps being so related that the latter remain with their tread surfaces horizontal and uppermost on both the ascending and descending portions of the tracks.
15. In a device of the class described, the combination with the tracks forming a continuous way, of a set of steps coöperating with said tracks each having a single riser, and driving connections for said steps, the tracks and steps being so related as to cause the steps to remain with their tread surfaces horizontal and uppermost and with the risers at the rear on the ascending portions of the track and at the front on the descending portions.
16. In a device of the class described, the combination with the steps, of the tracks forming a continuous way in a single vertical plane and with the ascending and descending portions covering the same surface and having curves at their ends adapted to guide the steps around said ends with their tread surface uppermost so that the noses of the steps will be in advance on the ascending portion of the tracks and in the rear on the descending portions of the tracks.
17. A moving stairway, guide tracks for the ends thereof adapted to change the direction of movement of the steps while presenting their tread surfaces uppermost.
18. A moving stairway, tracks for the ends thereof adapted to change the direction of movement of the steps while presenting their treads uppermost on the transporting runs.
19. In a device of the class described, the combination with the tracks forming a way, of a set of steps coöperating with said tracks, channel - tracks at the ends of the way adapted to change the direction of movement of the steps while presenting their tread surfaces uppermost on the transporting runs.
20. In a device of the class described, the combination with the tracks forming a way, of a set of steps coöperating with said tracks and having the leading and following wheels in different planes, and channel tracks at the ends of the way adapted to change the direction of the movement of the steps while presenting their tread surfaces uppermost.
21. In a device of the class described, the combination with tracks forming a way, of

a set of steps having extended axle bars provided with leading and following wheels in different planes and coöperating with the tracks, and channel tracks at the ends of the way adapted to change the direction of movement of the steps and present their tread surfaces uppermost on the runs and provided with interruptions to permit the passage of the extended axle bars, and guides coöperating with said axle bars to carry the steps past the interruptions.

22. In a device of the class described, the combination with the tracks forming a way, of a set of steps coöperating with said tracks and having extended axle - bars and the leading and following wheels in different planes, and channel tracks at the ends of the way adapted to change the direction of the movement of the steps while presenting their tread surfaces uppermost and provided with interruptions therein to permit the passage of the extended axle bars, and channel-guides coöperating with said axle bars to carry the steps past the interruptions.

23. In a device of the class described, the combination with tracks forming a way, of a set of steps coöperating with said tracks and having extended axle bars, driving chains connecting said axle bars, and channel tracks at the ends of the main tracks adapted to change the direction of movement of the steps and present their tread surfaces uppermost on the runs and having interruptions to permit the passage of the extended axle bars of the steps and having guides coöperating with said extended axle bars to carry the steps past the interruptions.

24. In a device of the class described, the combination with the tracks forming a way, of a set of steps coöperating with said tracks and having extended axle bars, driving chains connecting said extended axle bars, and channel tracks at the ends of the main tracks adapted to change the direction of the movement of the steps while presenting their tread surfaces uppermost on the runs and having interruptions therein to permit the passage of the extended axle bars of the steps, and having the channel-guides coöperating with said extended axle bars to carry the steps past the interruptions.

25. In a device of the class described, the combination with upper and lower tracks forming a continuous way, of an endless series of steps coöperating with said tracks, and driving connections for said steps, the tracks and steps being so related that the latter have their tread surfaces horizontal and uppermost on both the ascending and descending runs.

26. In a device of the class described, the combination with the tracks forming a continuous way in a single vertical plane, of an endless series of steps coöperating with said

tracks, and driving connections for said steps, the tracks and steps being so related that the latter present their tread surfaces horizontal and uppermost on both the ascending and descending runs.

27. In a device of the class described, the combination with tracks forming a continuous way, of a set of steps coöperating with said tracks and having leading and following wheels in different planes, and U-shaped carriages adapted to change the direction of movement of the steps while presenting their tread surfaces uppermost on both the ascending and descending runs, the tracks in the carriages crossing.

28. In a device of the class described, the combination with the tracks forming a way in a single vertical plane, of a set of steps coöperating with said tracks and having leading and following wheels in different planes, and U-shaped channel tracks at the ends of the way adapted to change the direction of movement of the steps while presenting their tread surfaces uppermost, the channel tracks for the leading wheels crossing those for the following wheels.

29. In a conveying apparatus, the combination with the ways having the rounded ends, of an endless conveyer coöperating with said ways, mechanism for driving said conveyer, and means connecting portions of said conveyer adjacent the ends so as to transmit the driving strain past said ends removing the tension from the conveyer as it passes said ends.

30. In a device of the class described, the combination with tracks forming a way, of a set of steps coöperating with said tracks, and channel tracks at the ends of the way adapted to change the direction of movement of the steps while presenting their tread surfaces uppermost on both the ascending and descending runs.

31. In a device of the class described, the combination with the tracks forming a way, of a set of steps coöperating with said tracks, and channel tracks at the ends of the way adapted to change the direction of the movement of the steps while presenting their tread surfaces uppermost.

32. In a conveying apparatus, the combination with the ways extending to different levels, of an endless conveyer coöperating with said ways, mechanism for driving said conveyer, and means coöperating with said conveyer on a certain portion of the ways to remove the tension thereon while passing said portion of the ways.

33. In a conveying apparatus, the combination with the ways extending to different levels, of an endless conveyer coöperating with said ways, mechanism for driving said conveyer, and means coöperating therewith to establish tension in a portion thereof and remove it on another portion.

34. In a conveying apparatus, the combination with the ways extending to different levels, of an endless conveyer coöperating with said ways, mechanism for driving said conveyer, and means coöperating with said conveyer to establish tension therein as it passes between predetermined points on said ways, and remove it between other points.

35. A moving stairway having upper and lower ascending and descending carrying portions and providing landings located in the same horizontal plane.

36. A moving stairway having upper and lower ascending and descending carrying portions and providing landings in the same horizontal plane at the top and bottom respectively.

37. A moving stairway having upper and lower ascending and descending carrying portions provided with tracks, and steps having front and rear wheels, each set of wheels leading on one portion and following on the other.

38. A duplex moving stairway comprising tracks forming a way in both directions between different levels, an endless series of steps moving in both directions on said way, and means to drive the steps in both directions.

39. A duplex moving stairway comprising tracks forming landings at different levels and inclined ways in both directions between the

levels, an endless series of steps moving in both directions on the tracks, and connected means to drive the steps in both directions.

35

40. A duplex conveyer comprising tracks in the same vertical plane forming a continuous way in both directions between different levels, an endless series of steps running on said way, a carriage at each end of the way, and tracks in the carriages to change the direction of travel of the steps and present their treads uppermost in both directions.

40

41. In conveying apparatus, a series of supports, guides for said supports forming a plurality of transporting runs having inclined portions, and reversers to transfer said supports between said runs, said reversers receiving and delivering said supports in substantially parallel position.

45

42. In conveying apparatus, a series of supports, guides for said supports forming a plurality of transporting runs having inclined portions, driving means for said supports, and reversers to transfer said supports between said runs, said reversers receiving and delivering said supports in substantially parallel position.
